UNITED STATES PATENT OFFICE.

JOHN S. SPENCER, OF NEW YORK, N. Y.

EYEGLASSES.

SPECIFICATION forming part of Letters Patent No. 292,959, dated February 5, 1884.

Application filed May 16, 1883. (No model.)

To all whom it may concern:

Be it known that I, JOHN S. SPENCER, a citizen of the United States, and a resident of New York, in the county of New York and State of New York, have invented certain new and useful Improvements in Eyeglasses, of which the following is a specification.

The invention has relation to improvements in eyeglasses, and especially to that class of eyeglasses in which elastic or yielding nose-pieces are employed.

The character of my improvements will be understood from the description hereinafter presented, reference being had to the accompanying drawings, in which—

Figure 1 is a view of an eyeglass, showing the construction of the nose-pieces and other parts in position. Fig. 2 is a view of a single glass. Fig. 3 is an enlarged perspective 20 view of one of the nose-pieces, and Fig. 4 is an inverted perspective view of the bridge-piece.

Referring to the drawings, *a a* represent the nose-pieces, the lower ends of which are bowed 25 and secured to pillars or standards attached to the frames *b* or to the glasses. The nose-pieces will be of a suitable kind and quality of metal, their upper parts being bent at an angle, and their extreme ends also bent to 30 form shoulders *c*, the functions of the shoulders being to prevent the escape of the upper end of the nose-pieces from their sockets in the bow-spring. The general shape of the nose-pieces and their position with relation to 35 the glasses are indicated with sufficient certainty in the drawings. The connecting or bow spring *f* is distinctive, in that its ends are bent and provided with sockets, (indicated by the letters *d d*,) in which the ends of the 40 nose-pieces are introduced, as indicated in Fig. 1, the escape or dislocation of the upper part of the nose-pieces being prevented by the shoulders *c*, which are held in contact with the socketed ends by the elasticity of the parts, 45 as shown. The bow-spring is attached near its ends to the pillars or supports *e*, in the customary manner, the sockets *d d* in its ends being properly arranged with relation to the nose-pieces.

It is obvious that the manner of attaching 50 the nose-pieces to the glasses is a matter of judgment, which may be varied according to the character of the frame and other circumstances. No difficulty will be experienced in practicing the invention in connection with 55 all kinds of eyeglasses, including what are known as "frameless glasses," as well as others.

I am aware that eyeglasses having nose-pieces the upper ends of which are capable of movement have heretofore been constructed; 60 but in every such instance it has been necessary to either cut an elongated slot in the ends of the nose-pieces or to cut a slot in the ends of the bridge and reduce the ends of the nose-pieces to move therein. In such case the construc- 65 tion is materially weakened, and frequently necessitates the employment of heavier metal than would otherwise be required. By my invention the upper ends of the nose-pieces are not reduced, nor are the ends of the bridge 70 slotted. According to my invention the ends of the nose-pieces are of full width, and the ends of the bridge carry sockets of proper size to receive the ends of the nose-pieces and to allow them to have a free movement. 75

What I claim as my invention, and desire to secure by Letters Patent, is—

The nose-pieces *A*, having their lower parts bowed and secured in place, and their upper parts bent toward the glasses and to form the 80 shoulders, said bent part and shoulder being of equal width and strength throughout, in combination with the bridge-piece, the ends of which are of equal proportions, and have applied thereon the sockets *d*, in which the 85 unreduced upper ends of the nose-pieces are retained and have free play, substantially as set forth.

Signed at New York, in the county of New York and State of New York, this 11th day 90 of May, A. D. 1883.

JOHN S. SPENCER.
